UNITED STATES PATENT OFFICE

WILLIAM ANDREW O'BRIEN, OF LOS ANGELES, CALIFORNIA

DESIGN FOR A CARD GAME SCORING BOARD

Application filed February 26, 1932. Serial No. 43,009. Term of patent 14 years.

To all whom it may concern:

Be it known that I, WILLIAM ANDREW O'BRIEN, a citizen of the United States of America, residing at Los Angeles, in the county of Los Angeles and State of California, have invented a new, original, and ornamental Design for Card Game Scoring Boards, of which the following is a specification, reference being had to the accompanying drawing, forming a part thereof.

Fig. 1 is a plan view of my new design, and Fig. 2 is a side elevation of my new design disclosing the construction of one side of the board, all of the sides being of the same general configuration.

I claim:

The ornamental design for a card game scoring board substantially as shown and described.

WILLIAM ANDREW O'BRIEN.
